(57) CLAIM

The ornamental design for a combined touch pad and buttons for a portable computer, as shown and described.

DESCRIPTION

FIG. 1 is a front, top and right side elevational perspective view of a combined touch pad and buttons for a portable computer showing our new design;

FIG. 2 is a front elevational view thereof;

FIG. 3 is a top plan view thereof;

FIG. 4 is a left side elevational view thereof;

FIG. 4 is a left side elevational view thereof;

FIG. 6 is a rear elevational view thereof;

FIG. 7 is a bottom plan view thereof.

FIG. 7 is a bottom plan view thereof.
The broken line drawing of a portable computer in all views is for illustrative purposes only and forms no part of the claimed design.
